ICE MAKING APPARATUS

Alvin H. Baer, Carbondale, Pa., assignor to The
Carbondale Machine Co., Carbondale, Pa., a
corporation of Pennsylvania

Application February 23, 1933. Serial No. 657,931

9 Claims. (Cl. 62—159)

Raw water used in the manufacture of artificial ice usually contains sufficient air in solution to cause the ice formed directly therefrom to be cloudy and/or substantially opaque unless the bubbles of air separating during the freezing be removed. It is common practice to agitate the water during freezing, by means of a jet of air delivered into the water and which will pick up or sweep out the small bubbles. 10 Thereby clear ice may be formed.

Among the objects of the invention are to more effectively agitate the water, to reduce the amount of power required for this operation, and to permit the use of smaller compressors or blowers 15 for a given size of tank.

I have found that intermittent agitation is as effective as continuous agitation if the periods of non-agitation be comparatively short, but not necessarily shorter than the periods of agitation. 20 I take advantage of this fact by delivering air to two or more sets of cans alternately or in succession and intermittently, and thus as the compressor is never, at any one time, delivering to both sets of cans, such compressor may be of 25 a size only approximately one-half that ordinarily needed for the two sets, and there is a very considerable saving in the cost of the apparatus and power required.

Intermittent delivery alternating for two cans 30 has heretofore been proposed, but so far as I am aware not in a practical and commercial form.

If the water be permitted to flow up into the air pipe during the time the air is shut off, the level of the water in the can will be continuously 35 varied, and each time the air is turned on for any given air pipe it must be forced out and a jet of water is formed before any air enters the can. Furthermore the release of the air pressure in the pipe when the supply is shut off, involves 40 a loss of the power required to compress such air as is thus permitted to directly escape to the atmosphere.

In my improved apparatus I employ a three-way valve for controlling the supply of compressed air to the two sets of cans alternately so that when one set is being supplied with compressed air, the other set is shut off from the supply and the compressed air in the individual 50 air pipes of the latter set is trapped. This serves to maintain a sufficient pressure in the air pipes at all times to prevent water from flowing up into them and prevents any direct escape of the air from the pipes except through the water while agitating. When the valve is reversed to admit 55 compressed air into the other set of pipes no

time is wasted in building up the pressure, there is no water in the pipes to be forced out, and the air begins immediately to bubble up through the water in the cans. As no water flows back into the pipes when the supply of compressed 60 air is shut off, no portion of the blowing time is wasted in ejecting this water from the pipes.

The valve is operated so as to automatically deliver the air to first one set of cans and then to another at the desired time intervals which 65 I have found may be several times each minute, although for some water supplies the time may be lengthened. With waters almost pure there may be a division of the cans into three or more sets and one on period to each two or more off 70 periods.

In the ordinary freezing of water in commercial cans it requires about forty-two hours if the brine is at 14° F. and about thirty-eight hours if the brine is at 12° F. By means of the 75 present invention the freezing time is reduced by one to two hours. This may be due in part to the lesser amount of heat delivered into the water with the air and in part to the more rapid freezing while the water is in a quiescent state 80 between successive periods of air delivery.

As another important feature of the present invention each air pipe has its discharge end shaped to eject the compressed air into two diverging streams toward the opposite end walls of 85 the can, thereby effecting a more balanced and regulated agitation of the water. By means of this construction I effectively create upward currents near the sides of the pipe and downward currents along the ice forming surfaces near the 90 ends of the can. Thus the direction of flow of water along the ice forming surface is opposite to that at which air bubbles forming on said surface tend to flow and they are more effectively swept off by the water current.

In the accompanying drawings there is shown for the purpose of illustration, one form of apparatus for carrying out my invention.

In these drawings:

Fig. 1 is a somewhat diagrammatic perspective view of a construction embodying my invention.

Fig. 2 is a section somewhat diagrammatic, taken along the line 2—2 of Fig. 1.

Fig. 3 is a section, somewhat enlarged, showing detail of the control valve.

Fig. 4 is a section through the lower part of a can with the drop tube therein and the water partly frozen.

100

105

110

Fig. 5 is a transverse section on the line 5—5 of Fig. 4, and

Fig. 6 is an elevation of a portion of one of the headers and a drop tube, the lower portion 5 of the latter being in section.

In this specific embodiment of the present invention, there is provided a series of freezing cans 10 of the standard type supported by any suitable means in a cold brine tank 11, and each 10 having the usual oblong, rectangular cross-section. These cans are filled with raw water and subjected to the freezing action of the cold brine in the tank.

Compressed air is delivered by a compressor 15 12 and conveyed to the individual cans in the tank by a pipe 13, a manifold or cross pipe 16, 17 and headers 14 and 15. Connected to each main header and extending directly above each lateral row of cans are branch headers 21 each 20 having drop pipes 22 delivering therefrom into the cans. Each branch header extends only about half way across the tank and supplies only one-half of the cans in its row. The branch headers extending in from one main header are approximately in line with the branch headers 25 extending in from the other main header so that approximately one-half of the cans in the tank are supplied by one main header and the other half by the other main header. The cans are 30 thus divided into two sets supplied with air from different main headers.

For controlling the supply of air to the main headers 14 and 15, a three-way valve 23 is disposed at the intersections of the manifold sections and the supply pipe 13. This valve may 35 be of the rotary or oscillating type, but is so constructed that it does not release air directly to the atmosphere and opens the supply to one manifold section while cutting it off from the other so that there may be a substantially uniform and continuous delivery of air from the 40 source of supply. As shown particularly in Fig. 3 this valve has a cylindrical chamber provided 45 with an inlet portion 24 adapted to be connected to the pipe 13, and a pair of outlet ports 25 and 26 adapted to be connected to the manifold sections 16 and 17 respectively. Mounted in the valve chamber is a valve member 27 of substantially skeleton form with a pair of segmental flanges 28 adapted to close either one of the 50 ports 25 or 26, but not to close the inlet port 24. This valve may be mounted to oscillate and the segmental flanges may be so disposed in 55 respect to the ports 25 and 26 that as one port begins to open the other will begin to close and the valve may move through a considerable range with one port remaining open and the other remaining closed. The closing of one of the ports 60 while air under pressure is being delivered to the valve chamber will cause the air in one of the manifold sections and the main header, branch header and drop pipes connected thereto, to be trapped and held under such pressure as is due to the head of water in the cans. Thus 65 no water can flow up the ends of the drop pipes and there will be no substantial variation in the pressure in the pipes, headers, manifold or supply pipe during the operation.

Any suitable means may be provided for oscillating the valve member at the desired time 70 intervals, and a disc or other intermittent valve may be used. I have shown somewhat diagrammatically a motor 31 connected by means of reduction gearing 32 and a crank or other driven 75 member to a link 33 pivotally connected to the

valve lever. The gearing may be such as to give a continuous back and forth movement to the link 33 or an intermittent movement with short periods of rest at each end of the stroke. The timing of this oscillating mechanism is so adjusted in respect to the speed of the motor that the reversals of the valve 23 takes place at least once each minute for the more difficult waters and longer for the other waters. I have found that this timing is very effective in securing the proper agitation of the water in the cans. 80 85

It will be noted that the valve has no outlet except to the headers, and as the air delivered to one header is shut off the air therein is trapped. It will also be noted that one of the ports 25, 26 opens as the other closes so that there may be a continuous uniform delivery from the compressor without substantial pressure variation and a continuous delivery of air to the water at a uniform rate. Therefore there is no substantial variation in the load on the motor and the motor may be of a size sufficient to deliver air to only one-half of the can at one time. Thus the cost of the motor is materially reduced with a corresponding reduction in the power required over that commonly provided for agitating mechanism for a tank of a given size. 90 95

As a further feature of the present invention each air pipe 22 is constructed at its discharge end to effect agitation of air therefrom in two diverging streams towards the ends of the can. Since these cans are of greater dimension in one direction than in the other the apparatus serves to eject the streams of air in the directions in which they will do the most good. 105 110

In the specific form shown, a partition 35 is mounted in the lower end of the pipe so as to divide the pipe into two parallel longitudinal passages which terminate in nozzles 36 and 37. 115 In order to direct the air jets in two regular diverging streams toward the end walls of the can the discharge opening of the nozzles 36 and 37 are above the lower end of the partition. This is preferably accomplished by cutting off 120 the lower end of the pipe 22 at opposite sides of the partition 35 and along downwardly converging lines so as to form substantially laterally directed outlets facing toward the end walls of the can. 125

I have found that by means of this construction, there is created upward currents near the sides of the pipe and downward currents near the end walls of the can, and the agitation of the water on both halves of the can is more balanced and more 130 uniform.

It will be noted that I would accomplish a similar result if the lower end of the tube was closed and openings or nozzles made through its sides near the lower end. Therefore the tube may be 135 varied in design and yet operate the same.

In order to prevent premature clogging of the discharge ends of the pipes by the ice formation on the bottom of the can, these ends are located a substantial distance above said bottom. 140

After a period of freezing and aerating, the main portion of the water in the cans will be frozen solid, and a relatively small cavity remain containing the unfrozen water and substantially 145 all of the impurities. Substantially all of the air will have been released and come to the surface. The unfrozen water and its impurities are then removed from the can and the cavity filled with fresh water which is then permitted to con- 150

tinue freezing at a relatively slow rate until a substantially solid block of ice is formed.

Having thus described my invention, what I claim as new and desire to secure by Letters Patent is:

1. In the art of manufacturing ice by an apparatus comprising a plurality of sets of cans of substantially equal number and containing water to be frozen, the method which includes the steps of blowing compressed air into the water in the cans of the sets in succession and intermittently to agitate the water in said cans, and maintaining pressure in said pipes at all times during the entire blowing period to prevent rise of water in said pipes during this period.

2. A can ice plant including two substantially equal sets of cans, a source of compressed air supply, an air supply pipe leading from said source of compressed air, a pair of headers connected to drop pipes in said cans and connected to said supply pipe, and a valve at the intersection of said headers and said supply pipe for controlling the supply of compressed air to said headers and acting to trap air in one header while delivering air to the other header in alternate succession.

3. An ice making plant including two sets of cans each having an air inlet pipe, a compressor of a capacity substantially only sufficient to supply agitating air at the usual rate to approximately half of said cans, a pair of headers one connected to the air pipes of one set of cans and the other connected to the air pipes of the other set of cans, a supply pipe connecting said compressor and said headers, a three-way valve operable to connect either of said headers to said supply pipe and to close the other against return flow of air from the air pipes connected thereto, and means for operating said valve to reverse the connections to said headers at intervals of less than one minute.

4. An apparatus for manufacturing ice, including two sets of cans adapted to hold water to be frozen, a source of compressed air supply, a pair of headers, and a three-way valve having an inlet port communicating with the source of compressed air supply, a pair of outlet ports communicating respectively with said headers, and a valve member which closes one of said outlet ports when the other outlet port is opened.

5. An apparatus for blowing air through a body of water, including a can for said water, a pipe extending downwardly in the water of the can and having the lower end thereof spaced a substantial distance above the bottom of the can, and a partition plate in said pipe forming a pair of discharge nozzles on the opposite sides of said plate, the outlet opening of each nozzle extending above the lower edge of the partition plate, whereby compressed air may be ejected from said pipe in two well-regulated and diverging streams.

6. An apparatus for agitating a body of water to remove air and impurities therein and to form marketable ice, including a can for holding water to be frozen and having an oblong, rectangular cross-section, a pipe extending into said can and having the discharge end spaced above the bottom of said can, and a vertical partition plate inside said pipe, forming a pair of passages at the discharge end of said pipe, and extending substantially at right angles to the sides of the can, said pipe having a pair of outlet openings

disposed above the lower edge of the partition plate, whereby compressed air may be ejected from said pipe in two regulated and diverging streams towards the end walls of said can.

7. An apparatus for blowing air through a body of water, including a can for said water, a pipe extending downwardly in the water of the can and having the lower end thereof spaced a substantial distance above the bottom of the can, and a partition plate in said pipe forming a pair of discharge nozzles on the opposite side of said plate, the lower end of the pipe being beveled on opposite sides of the plate towards the lower end of said plate to form outlet openings for said nozzles above the lower edge of said plate, whereby compressed air may be ejected from said nozzles in two well-regulated and diverging streams.

8. An apparatus for manufacturing artificial ice, including a brine tank, two substantially equal batches of cans adapted to hold water to be frozen and supported in said brine tank, a source of compressed air supply, an air supply pipe leading from said source of compressed air, a pair of headers branching from the outlet of said pipe, a valve at the intersection of said headers and said supply pipe for controlling the supply of compressed air to said headers, a pipe extending into the water in each can, the pipes in one batch of cans communicating with one header, and the pipes in the other batch of cans communicating with the other header, the lower end of each pipe being disposed a substantial distance above the bottom of its respective can, whereby ice formation in the bottoms of the cans does not prematurely clog the discharge ends of said pipes, and a three-way valve at the intersection of said headers and said supply pipe, and having an inlet port communicating with the source of compressed air supply, a pair of outlet ports communicating respectively with said headers, and a valve member which closes one of said outlet ports when the other outlet port is opened, and automatically operable means for oscillating said valve member periodically from one position to another to alternately open one outlet port and close the other, whereby compressed air is blown in alternate succession through the water in the cans of the two batches to intermittently agitate said water.

9. An ice making plant including a plurality of substantially equal sets of cans adapted to hold water to be frozen, a corresponding number of headers, a source of compressed air supply for said headers, a plurality of substantially vertical pipes, each extending centrally into the interior of a corresponding can, the lower end of each pipe being disposed a substantial distance above the bottom of its respective can whereby ice formation in the bottom of the can does not prematurely clog the discharge end of said pipe, the pipes in each set of cans communicating with their respective headers, valve means for controlling the supply of compressed air to said headers and acting to deliver air to one header while trapping air in the other headers, means for automatically operating said valve means in predetermined intervals to deliver air into said sets of cans in succession, and means connected to the outlet ends of the pipes for directing compressed air therefrom in diverging streams.

ALVIN H. BAER.
